FIG. 3.

UNITED STATES PATENT OFFICE.

EUGENE H. BALLOU, OF PAWTUCKET, RHODE ISLAND, ASSIGNEE TO DRAPER CORPORATION, OF HOPEDALE, MASSACHUSETTS, A CORPORATION OF MAINE.

WEFT-THREAD CATCHER AND HOLDER FOR AUTOMATIC WEFT-REPLENISHING LOOMS.

1,272,599.

Specification of Letters Patent. Patented July 16, 1918.

Application filed August 6, 1917. Serial No. 184,702.

To all whom it may concern:

Be it known that I, EUGENE H. BALLOU, of Pawtucket, in the county of Providence and State of Rhode Island, have invented a new

5 Weft-Thread Catcher and Holder for Automatic Weft-Replenishing Looms, of which the following is a specification.

In automatic weft replenishing looms the spare weft carriers are usually maintained in 10 a magazine mounted on a fixed part of the loom and the end of each weft carrier is attached to a weft end holder. Then, when a weft carrier is supplied to the loom and the shuttle is picked from the replenishing side 15 of the loom to the opposite side, a strand of weft is left extending from the weft end holder to the selvage of the cloth. It is the usual practice to cut this strand of weft close to the selvage so that a loose end of weft is 20 left secured at one end to the weft end holder. This loose weft end is apt to get caught by the picker and may get broken off and carried into the shed with a resulting blemish in the cloth. The purpose of the 25 present invention is to provide a catcher and holder for this loose weft end which will maintain it out of the way of the picker until the weaver has opportunity to visit the loom and remove it altogether.

30 The invention is illustrated in the accompanying drawings, wherein—

Figure 1, is a front view of so much of the replenishing end of the loom as is necessary for an understanding of the invention. Fig. 35 2, is a plan view of a portion of the lay and shuttle box at the replenishing side of the loom. Fig. 3, is a vertical cross section in the plane indicated by the line 3—3 in Fig. 1.

Fig. 1 illustrates the lay A; the shuttle 40 box B, at the replenishing side of the loom; the shuttle C, within the box; the picker D; a rotary magazine E, of the well known Northrop type (as illustrated for example in United States Letters Patent of Northrop 45 No. 529,940, November 27, 1894); a weft end holder F, carried by the magazine; a weft carrier G, in the magazine; and a strand of weft H, extending from the weft end holder to the selvage of the cloth shown 50 at I, in Fig. 2. This condition of the weft end H, exists until it is cut close to the selvage by a thread cutter of any of the now well known varieties. One such cutter is illustrated in United States Letters Patent 55 of Draper and Stimpson No. 585,465, June

29, 1897. When the weft end H, is cut it is left loose and it is the object of the present invention to catch and hold this loose end so as to keep it out of the way of the picker.

As shown in the drawings the lay is 60 equipped with a bracket J, at the replenishing side of the loom and between the warp and the mouth of the shuttle box. This bracket J, is secured to the front side of the lay and it has a forward extension K, and a 65 top L, which is secured to the back of the lay and overhangs the race plate M, and the shuttle path, being a sufficient distance above the race plate to afford room for the free passage of the shuttle. The extension K, extends forwardly of the race plate, the front of the lay and the front of the shuttle box, and constitutes a holder for the weft end. A thread catcher N, is pivoted at O, to the top plate L, extends 70 downwardly through a slot P, therein, and rests at its lower free end upon the bottom of the holder K, as shown in Fig. 3, thereby closing the rear of the holder. The lower end of the catcher N, is beveled as 75 shown at Fig. 3, so as to afford a flaring mouth or entrance Q, for the weft end. The catcher is forward of the front of the shuttle box.

When a fresh weft carrier has been inserted in the shuttle and the shuttle has been picked to the other side of the loom the freshly laid strand of weft is beaten up to the fell of the cloth to the position shown in Fig. 2. The lay then retreats from the fell 90 of the cloth as indicated in Fig. 2, thus leaving the weft end H, extending at an angle to the length of the lay from the fell and selvage of the cloth to the weft end holder F. During this retreat of the lay the weft 95 end H, is guided upwardly and forwardly by the outwardly and upwardly curving guide R (Fig. 3), of the bracket J, into the flaring entrance Q, below the catcher N. This inclined thread directing guide is between the shuttle path and the holder and guides the weft thread to the catcher and the holder. Then as the lay continues its retreat the weft end passes beneath the catcher N, and into the chamber of the holder K, 100 which is forward of the catcher N. The weft end is sufficiently taut between the selvage and the weft end holder, and the catcher N, is sufficiently light so that the thread lifts the catcher and gets into the holder. Then, 110

after the weft end has been cut close to the selvage, its loose end remains in the holder K, forward of the catcher N, and the shuttle path and out of the path of the 5 picker until such time as the weaver can attend to its removal.

The new catcher and holder herein set forth are of especial value and importance in a weft replenishing loom of the character 10 set forth in Letters Patent of the United States, No. 1,244,827, Oct. 30, 1917. In accordance with that patent, when a change of weft is called the shuttle box stops during its forward movement when about half way 15 forward while the lay continues its forward course so that the shuttle and shuttle box are standing still at the time a fresh weft carrier is transferred from the magazine into the shuttle. This involves a position 20 of the magazine farther back than in the loom shown in the aforesaid Northrop Patent No. 529,940, wherein a fresh weft carrier is transferred from the magazine to the shuttle when the lay and the shuttle box are 25 substantially at their most forward positions. By reason of this rearward location of the magazine in the loom of the aforesaid Patent No. 1,244,827, the place on the weft end holder F, where the newly inserted 30 weft end H, is located is closely above the picker when the picker acts with the result that there is an added danger of the loose weft end being caught. When, however, the thread holder and catcher herein set forth 35 are employed the loose weft end is held sufficiently forward of the picker to prevent the weft end being caught thereby.

I claim—

1. A weft replenishing loom having, in

combination, a weft end holder carried by 40 the lay and extending in front of the race plate of the lay and located close to the mouth of the shuttle box at the replenishing side of the loom; a pivoted gravity catcher closing the rear of the holder and resting on 45 the bottom of the holder with a flaring entrance between it and the bottom of the holder facing the shuttle path; and an inclined weft thread directing guide between the shuttle path and the thread catcher. 50

2. A weft replenishing loom having, in combination, a weft end holder carried by 55 the lay and extending in front of the race plate of the lay and located close to the mouth of the shuttle box at the replenishing side of the loom; and a pivoted gravity catcher closing the rear of the holder and resting on the bottom of the holder with a flaring entrance between it and the bottom of the holder facing the shuttle path. 60

3. A weft replenishing loom having, in combination, a weft end holder carried by 65 the lay and extending in front of the race plate of the lay and located close to the mouth of the shuttle box at the replenishing side of the loom; and a pivoted gravity catcher closing the rear of the holder and resting on the bottom of the holder. 70

4. A weft replenishing loom having, in combination, a weft end holder carried by 75 the lay and extending forward of the shuttle box at the replenishing side of the loom, and a movable catcher normally closing the rear of the holder.

In witness whereof, I have hereunto signed my name.

EUGENE H. BALLOU.
